UNITED STATES PATENT OFFICE.

ARTHUR H. HAUGEN, OF TINTAH, MINNESOTA.

CAR-DOOR HOLDING AND SEALING DEVICE.

Application filed June 23, 1924. Serial No. 721,620.

To all whom it may concern:

Be it known that I, ARTHUR H. HAUGEN, a citizen of the United States, residing in the city of Tintah, county of Traverse, and 5 State of Minnesota, have invented new and useful Improvements in Car-Door Holding and Sealing Devices, of which the following is a specification.

My invention relates to improvements in 10 car door holding and sealing devices, one object thereof being to provide simple and durable means readily applicable to a car structure and easily adjusted to hold the ordinary car door in doorway closing position and to seal the door at the sides thereof against leakage of grain or other lading.

Another object is to provide a device of 15 the present nature for cars adapted to accommodate doors of different widths and 20 thickness and designed to be quickly and easily operated to free the door when a car is loaded as well as when the same is empty.

A further object is to apply a door holding and sealing device, as above, the same 25 being readily applicable to the various freight cars and designed to avoid the driving of nails into door sections and door frames, whereby injury thereto by such nailing is eliminated.

30 With the foregoing and other objects in view, which will appear in the following description, the invention resides in the novel combination and arrangement of parts and in the details of construction hereinafter described and claimed.

In the accompanying drawings, Fig. 1 is 35 an elevational view of my improvement, the same being illustrated as applied to a car structure and in use in holding and sealing 40 a door closing the doorway of the car, said car structure being shown in section longitudinally of the car; Fig. 2 is a sectional view taken on the line 2—2 of Fig. 1; Fig. 3 is a perspective view enlarging upon Fig. 45 1 in the details of my improvement and its application to a car structure; Fig. 4 is a sectional view taken on the line 4—4 of Fig. 3 and Fig. 5 is an elevational view illustrating, particularly, the upper end of the 50 segmental door holding drum.

Referring to the drawings, wherein similar reference characters have been employed to designate similar parts throughout the several views, it will be observed that the 55 illustrated embodiment of my invention, includes two opposed door engaging members

A, B shown as applied to the usual freight car structure including a floor 10, sides 11 and lining 12, said structure having an ordinary doorway therein framed at the sides 60 thereof by posts 13, 13^a and at the top by a head-rail 14.

One member A or clip-bar, as it may be termed, is preferably formed of metal of heavy gauge. Said member comprises a 65 web or shank 15 with a right angular attaching flange 16 at one side thereof and an opposed abutment flange 17 at the outer side thereof. The inner angle between the web 15 and flange 17 is slightly greater than 70 90° to produce a wedging and compensating effect as will more fully hereinafter appear. The attaching flange 16 is formed with spaced, lateral slots 16^a therein. Lag screws 18 inserted through these slots and 75 threaded in the post 13 secure the clip-bar A in upright position on said post, said slots permitting of horizontal adjustment of said clip bar A, when that is desired.

The door engaging member B opposite 80 said clip-bar A, includes an upright segmental drum b, trunnioned at its ends to turn on the axis thereof, also a handle 19 for turning the drum, and latching mechanism c for releasably securing the drum in 85 door holding and sealing relation. The drum b comprises a semi-cylindrical shell 20 of relatively light sheet metal and quadrant-like head and bottom pieces 21, 22. A trunnion-boss 23 depending from the bottom 90 piece 22 is journaled in a bearing plate 24 seated in the car floor 10, said plate having a circular recess 24^a in its upper face, adapted to revolvably receive said bottom piece, 95 said recess being of a depth equal to the thickness of said bottom piece 22. A trunnion-stud 25 rising from the top piece 21 of the drum b is journaled in a bracket 26 suitably attached, as by means of bolts 27, 100 to the post 13^a or other part of the car structure.

The handle 19 is hinged on the drum b near its upper end, said handle being swung outwardly of the drum and thus supplying a lever for turning the same, when that is desired.

The latching mechanism c comprises a toothed or ratcheted quadrant 28, secured to the upper face of the top piece 21 of the drum b, and a dog 29, said dog being pivoted at one end on the bracket 26 and yieldingly held at its other end in cooperative relation 110

with respect to the ratchet quadrant 28 by means of a spring 30.

In the use of my device, a car door, in sections or unitary form, is applied to a doorway by inserting one edge of the door structure between the post 13 and flange 17 of the clip-bar A. Sliding said door into the clip as far as the angularly related flange 17 will permit, results in the wedging of said door by said flange 17 against said post 13. In this connection it will be noted that the clip-bar A accommodates doors of different thicknesses. Having thus arranged the door, it will be understood that the edge thereof opposite the clip-bar A will lap the post 13^a more or less according to the width thereof. These variations in dimension are provided for in the diameter of the drum b. Lifting the handle 19 and turning the drum b by said handle to swing the clamping edge 20^a of the shell 20 to the left (Fig. 3), results in swinging the drum b around the adjacent edge of the door structure and bringing said clamping edge 20^a of said shell to bear against the margin of the door. In this movement of the drum b, the dog 29 slides over the teeth of the quadrant 28. Applying sufficient power to the handle 19, the shell 20 forces the door tightly against the post 13^a. Dropping behind the passing teeth of the quadrant 28, the dog 29 prevents retraction of the drum b, which, through the shell 20, clamps the door closed against the post 13^a (Fig. 2), thus preventing edgewise movement of the door out of its closed, wedged position against the post 13^a. In loading the car to a height above the handle 19 in its normally depending position, said handle is swung upward and left standing in that relation to permit of ready access thereto when it is desired to unload the car. To free the door after it is clamped in place, as above explained, the dog 29 is lifted to permit of retraction of the drum b and said drum thereafter swung back into initial position (Fig. 3) by means of the handle 19. Thus freed, the door in whole or in sectional part, according to the structure thereof, may be shifted sidewise out of engagement with the clip-bar A and thereafter removed from the car. At this point, attention is invited to the fact that the shell 20, owing to its circular cross-sectional form, may be turned in the lading of a

car with a minimum of resistance. This feature, which allows for the use of relatively light and inexpensive stock in the drum b, and the ability of the shell 20 to accommodate doors of different widths are important advantages.

In cars fitted with a lining, as at 12, a space is left between the lining 12 and post 13^a to receive the drum b, said lining being brought up closely to the shell 20 of the drum to form a grain tight joint between said lining and shell. Thus arranged, the drum b functions, as above explained, and, further, forms a seal for the lading of a car by guarding it away from the edge of the door against the post 13^a.

Changes in the specific form of my invention, as herein disclosed, may be made within the scope of what is claimed without departing from the spirit of my invention.

Having described my invention, what I claim as new and desire to protect by Letters Patent is:

1. The combination with a car having a space between the lining thereof and an adjacent door post, of a door clamp and sealing guard comprising an upright, semi-cylindrical shell axially mounted in said space and closely brushing the adjacent terminus of said lining, means for turning the shell, said shell, when turned into one position being adapted to encase the adjacent edge of the door and bear at one edge against the margin of said door for holding the door against said post, and, when turned to retracted position, to free the door, and releasable means for securing said shell against retraction.

2. The combination with a car, of a door clamp comprising an upright, semi-cylindrical shell mounted to turn on its axis into and out of the angle between a door post and the siding of a car, means for swinging the shell from position of disuse within said angle into projected position, said shell in said latter position being adapted to receive and encase the edge of a door lapping said post and to bear at an edge thereof against the door and thereby clamp said door against said post, and means for releasably securing said shell in door holding position.

In testimony whereof, I have signed my name to this specification.

ARTHUR H. HAUGEN.
